(57) **CLAIM**

The ornamental design for a party popper, as shown and described.

DESCRIPTION

FIG. 1 is a perspective view of a party popper in accordance with my new design, in closed position;

FIG. 2 is a side elevational view thereof, the opposite side being a mirror image;

FIG. 3 is a front elevational view thereof;

FIG. 4 is a rear elevational view thereof;

FIG. 5 is a top plan view thereof;

FIG. 6 is a bottom plan view thereof; and,

FIG. 7 is a perspective view thereof in the open position. Throughout the figures broken lines are for purposes of illustration only and form no part of the claimed design.
